UNITED STATES PATENT OFFICE.

HERMANN MATTES, OF ULM-ON-THE-DONAU, GERMANY, ASSIGNOR TO C. D. MAGIRUS AKTIENGESELLSCHAFT, OF ULM-ON-THE-DONAU, GERMANY, A CORPORATION OF GERMANY.

MECHANICAL LADDER.

Application filed June 29, 1925, Serial No. 40,205, and in Germany February 2, 1925.

This invention relates to mechanical ladders and more especially to a device for tilting a mechanical ladder about a pivot pin disposed at right angles to the plane of the ladder, and the invention consists chiefly in the arrangement of a communicating pipe system, the liquid of which flows in the direction of inclination when the ladder is on sloping ground and thereby throws a gear in or out so that the ladder is automatically brought to the upright position.

A construction according to the invention is diagrammatically illustrated in the accompanying drawings in which,

15 Figure 1 shows the ladder on sloping ground,

Figure 2 is a side elevation, partly in section, of an embodiment of the invention,

Figure 3 is a plan of Figure 2,

20 Figure 4 is an enlarged cross sectional view of the tilting mechanism,

Figure 5 is a section taken on the line 5—5 of Figure 4, and

Fig. 6 is a sectional view of the mechanism 25 of the pressure cylinder.

The drawings illustrate a fire ladder of any suitable type, adapted to be erected by being rotated about a horizontal axis 41 in the known manner. If the ladder truck 30 stands on sloping ground, the ladder, upon being erected, will assume a laterally inclined position as shown at *a* in Fig. 1. In order to bring it into the upright position *b* shown in Fig. 1, it must be rotated in its 35 own plane about a pivot pin 3 perpendicular to said plane. In the present invention, this is accomplished by rotating a threaded shaft 22, bearing a nut 29 having a shank which engages the ladder to rotate it in the proper 40 direction.

As seen in Fig. 4, shaft 22 is journaled, at 27 and 28, in frame members 23, and is threaded to receive a nut 29, having a shank 32 which passes through an aperture in plate 31. Plate 31 is secured to the longitudinal members of ladder 30. Bevel gears 16 are splined to shaft 22. Shift lever 15 has a forked end 39 which engages an annular groove 38 in the collar 42 of gears 16. Lever 45 15 is pivoted at 37 to bracket 33, in which shaft 26 is journaled, and at its other end is connected by link 14 and bell crank 13 to rod 12.

The shaft 22 is provided with hand wheels

43 by means of which it may be manually 55 rotated if desired, but it is normally driven from the vehicle motor (not shown) by means of shafts 24, 25 and 26 connected together by gears, and by means of a pinion 21 which is mounted on the shaft 26 to selectively engage either of the bevel gears 16. Gears 16 are moved on the shaft 22 to the right or to the left by means of a pressure cylinder 8 having a piston 11 connected by means of rod 12, bell crank 13, and link 14 to the shift lever 15. Cylinder 8 is provided with a sleeve valve 9 which admits liquid under pressure through a supply pipe 19 to either face of the piston and discharges it through a discharge pipe 20. The details 70 of the valve 9 are best shown in Fig. 6, in which it is seen that the flow of liquid through supply pipe 19 and valve 9 is directed to either face of piston 11 by the rotation of the valve by means of an arm 35, 75 keyed thereto. When the valve is in the position shown in Fig. 6, liquid flows into the rear end of the cylinder, urging the piston forward, while the liquid in the forward end of the cylinder passes out via exhaust port 34 to the discharge pipe 20. Valve 9 is automatically controlled by means of a rod 10 and lever 4 pivoted at its center to pin 3, the ends of the lever being connected to the rods 6 of pistons 5. The two pistons 5 travel in cylinders 1 which are in communication with each other through a pipe 2, the interiors of the cylinders, to the rear of pistons 5, being filled with a heavy liquid such as mercury.

90 The tilting operation is as follows:

If the ladder is erected on sloping ground, the pistons 5 will move as the levels of the liquid in the cylinders 1 tend to become equalized through the pipe 2. The pistons 95 will thereby be moved in their cylinders, causing lever 4 to turn about its pivot 3, which will move rod 10 to open sleeve valve 9 to admit liquid under pressure to the piston 11. The latter will produce through the 100 rod 12, bell crank 13, link 14 and lever 15 an engagement of one of the gears 16 with the pinion 21, thereby rotating shaft 22. Nut 29 will be moved along shaft 22, thereby 105 rotating the ladder in its own plane about pivot pin 3 until pipe 2 reaches the horizontal position, whereupon the liquid will act on pistons 5 to move lever 4 into the

horizontal position and thereby turn valve 9 to its neutral position. This allows pinion 21 to disengage from bevel gears 16 and the ladder ceases to rotate. If the plane of the 5 ladder is a vertical plane, the result of the tilting operation just described is to move the ladder to a truly vertical position, but if the plane of the ladder is an inclined plane, the result is merely to move the ladder until its projection on a vertical plane passed through the lower ends of its longitudinal members is vertical. In either case, each rung of the ladder will be horizontal and the position of the ladder as a whole 10 may be spoken of as "upright" as distinguished from "laterally inclined". Also, I use the term "plane of the ladder" to designate a plane passing through the axes of the longitudinal members of the ladder.

20 In order to prevent the nut 29 from striking the bearings 27 and 28, there is provided a rod 17, pivoted at one end to link 40 which in turn is pivoted to the fixed frame of the truck, and pivoted at its other end to 25 arm 36, which is fixed to arm 35 and to valve 9. A stop pin 18 is mounted adjacent each end of rod 17 in such position that it will be engaged by the longitudinal members 30 of the ladder before nut 29 engages bearing 27 or 28. The engagement of stop pin 18 moves rod 17 longitudinally, thus turning arm 36 and valve 9 to neutral position to prevent further rotation of the ladder about pin 3.

35 Having now particularly described and ascertained the nature of my invention and in what manner the same is to be performed, I declare that what I claim is:—

40 1. In a mechanical ladder, a frame, a ladder pivotally mounted thereon, a threaded shaft journaled in said frame, a pair of gears on said shaft, a pinion adapted to selectively engage said gears, a nut mounted on said shaft, and engaging said ladder, and means actuated by movement of the ladder 45 for automatically disengaging the pinion from the gears when the nut has reached a predetermined position on said shaft.

50 2. In a mechanical ladder, a frame, a ladder pivotally mounted thereon, a threaded shaft journaled in said frame, a pair of gears splined to said shaft, a pinion adapted to selectively engage said gears, a nut mounted on said shaft and adapted to engage said ladder to turn said ladder about its pivot, and means actuated by movement of the ladder for moving said gears longitudinally of said shaft to disengage the gears 55 from the said pinion.

60 3. In a mechanical ladder, a frame, a ladder pivotally mounted thereon, a threaded shaft journaled in said frame, a pair of gears splined to said shaft, a pinion adapted to engage said gears, a nut mounted on said shaft and having operative engagement with

70 said ladder to cause it to turn about its pivot, means for driving said pinion, and means actuated by movement of the ladder for disengaging said gears from said pinion when the ladder has moved through a predetermined angular distance relative to said frame.

4. In a mechanical ladder, a supporting frame, a ladder pivotally mounted thereon, driving mechanism for rotating said ladder 75 about said pivot, and a control for said driving mechanism, said control comprising a pair of intercommunicating cylinders mounted on the ladder, pistons in said cylinders, a heavy liquid in said cylinders below the pistons, a lever connected to said pistons, and a mechanical connection between said lever and said driving mechanism.

5. In a device of the class described, 85 a supporting frame, a ladder pivotally mounted thereon for rotation in its own plane, a shaft mounted in said frame and having a threaded portion, a nut mounted on said threaded portion and engaging the ladder, bevel gears splined to said shaft, a pinion having selective engagement with said bevel gears, and means for controlling the engagement of the pinion with said gears, said means including a gravity actuated fluid control operated by lateral inclination of the ladder, and a connection between the control and the pinion.

90 6. In a device of the class described, 100 a supporting frame, a ladder pivotally mounted thereon for rotation in its own plane, driving mechanism for imparting such rotation to the ladder, and a gravity actuated control mechanism operated by lateral inclination of the ladder, said control 105 mechanism comprising a pair of intercommunicating vessels, fluid in said vessels, a movable member adapted to be actuated by said fluid, and a mechanical connection between said movable member and said driving mechanism.

110 7. A device of the class described, 115 comprising a supporting frame, a ladder pivotally mounted thereon for rotation in its own plane, driving mechanism for imparting such rotation to the ladder, said driving mechanism including a shiftable gearing for reversing the direction of such rotation, means for shifting said gearing, and a control for said shifting means, said control being operated by lateral inclination of the ladder and comprising a pair of intercommunicating vessels, liquid in said vessels, and a mechanical connection between said liquid and said shifting means whereby the 120 pressure of the liquid in said vessels operates to control the shifting of said gearing.

125 8. A device of the class described, 130 comprising a pivotally mounted ladder, driving mechanism for rotating said ladder about its pivot, said mechanism including shiftable

- gears, means for shifting said gears including a power-operated piston, and control means for said shifting means comprising a pair of intercommunicating liquid containers fixed to said ladder, movable members in said containers adapted to be actuated by the liquid in said containers, and a connection extending from said movable members to said shifting means.
- 10 9. A device of the class described, comprising a support, a ladder pivoted to said support, driving mechanism for rotating said ladder about its pivot, said mechanism including gearing shiftable to reverse and neutral positions, means for shifting said gearing including a cylinder, a power-operated piston therein operative to shift said gearing, and control means for said piston comprising a liquid container fixed to said ladder, a movable member in said container adapted to be actuated by the liquid in said container, and a connection between said movable member and said cylinder.
- 15 10. In combination, gearing shiftable to reverse and neutral positions, means for shifting said gearing, and control means for said shifting means comprising a pair of intercommunicating liquid containers inclinable to vary the liquid levels in said containers, movable members in said containers adapted to be actuated by the variations in said liquid levels, a pivoted member connected to said movable members, and a connection between said pivoted member and said shifting means.

In testimony whereof I affix my signature.

HERMANN MATTES.
